UNITED STATES PATENT OFFICE.

EDWARD SARGENT, OF NEW LISBON, WISCONSIN, ASSIGNOR TO CHARLES A. LEICHT, OF SAME PLACE.

LOCK.

SPECIFICATION forming part of Letters Patent No. 640,956, dated January 9, 1900.

Application filed January 19, 1897. Serial No. 619,824. (No model.)

To all whom it may concern:

Be it known that I, EDWARD SARGENT, a citizen of the United States, residing at New Lisbon, in the county of Juneau and State of Wisconsin, have invented a new and useful Improvement in Mortise Door-Locks, of which the following is a specification.

My invention relates to an improvement in mortise door-locks in which I abandon springs and make use of a pendent weight combined with a vertical curved locking-bar.

The object of this invention is to produce a lock that will automatically lock by gravity.

Furthermore, the object of the invention is to produce means for causing a positive action of the locking-bolt when released.

A further object of the invention is the production of a lock which will prove strong, durable, and efficient and at the same time comparatively inexpensive, since it is of few parts, which are readily removable should it be necessary to renew those worn or broken.

With the above and other objects in view the invention consists in the details of construction, as well as in the arrangement and combination of parts, to be hereinafter more fully set forth, and specifically pointed out in the claims.

In describing the invention in detail reference will be had to the accompanying drawings, forming part of this specification, wherein like characters of reference denote corresponding parts in both views, in which—

Figure 1 is a plan view of my lock with the casing on one side removed. Fig. 2 is a vertical sectional view on the line O P of Fig. 1.

In the drawings, A denotes a pendant having formed therewith an apertured head H to receive the door-spindle F. A stud d is formed on the pendant and is adapted to engage the pinion D and elevate it as the pendant is elevated from its normal position, as shown in Fig. 1, it being understood that as the pendant is elevated to the position shown in dotted lines the pinion will be partially rotated, thus actuating the locking-bolt B through the toothed rack, which is engaged

by the pinion. Should the pendant be turned, as indicated in dotted lines, the locking-bolt will be drawn up and the lower end thereof will be brought within the casing. Friction-rolls a a operate in slots 1 of the locking-bolt, as will be apparent.

The locking-bolt is provided with a notch on its upper edge to receive a gravitating detent C, said detent consisting of a body having slots 2 to receive the friction-rolls a a, similar to those employed in connection with the locking-bolt. In the lower edge of the detent I provide a notch, forming a wall or shoulder against which the key operates to withdraw the nose of the detent from engagement with the locking-bolt, it being understood that said detent automatically operates to engage the bolt by reason of gravity.

In practice it has been found desirable to secure the detent in its position either to engage the bolt or in its elevated position out of engagement therewith. This I accomplish by a thumb-screw which binds the detent to the lock-casing. For instance, should it be desirable to lock the door from the inside the detent can be dropped into position with the locking-bolt, and after the screw is tightened the key cannot operate it. Likewise if it is found desirable to have the door opened by simply turning the knob the detent can be secured in its elevated position in the same manner, when the locking-bolt will be free to operate.

The operation and advantages will, it is thought, be understood, it being noted that changes in the details of construction may be resorted to without departing from the spirit of my invention.

Having fully described my invention, what I claim as new, and desire to secure by Letters Patent, is—

1. In combination, a pendant having a spindle-barrel, a pinion mounted on the barrel, a stud on the pendant for actuating the pinion, a gravity-bolt having a rack engaged by the pinion, said bolt having slots to receive friction-rolls operating in slots, a detent having

slots, friction-rolls operating in the slots, said
detent being notched to receive a key as and
for the purpose described.

2. In combination, a pendant having a spin-
dle-barrel, a spindle for operating the pend-
ant, a pinion mounted on the barrel, a stud
on the pendant to engage the edge of the pin-
ion, a curved locking-bolt having a rack on

its upper edge, a gravitating detent engaging
a notch of the locking-bar, said detent hav- 10
ing a notch to receive a key, as and for the
purpose specified.

EDWARD SARGENT.
